Leslie F. Carter

UNITED STATES PATENT OFFICE

LESLIE F. CARTER, OF LEONIA, NEW JERSEY, ASSIGNOR, BY MESNE ASSIGNMENTS, TO SPERRY PRODUCTS, INC., OF BROOKLYN, NEW YORK, A CORPORATION OF NEW YORK

RECORDING STYLUS

Application filed February 16, 1927. Serial No. 168,515.

This invention relates to a new type of recording stylus and more particularly to the class of metal styli which are employed most usually in connection with metallic recording paper, that is, recording paper having a metallized surface. The type of stylus heretofore employed for such recording has been a metal rod turned down to a point at its recording end. The use of such a stylus had many serious disadvantages, among which were, first, that the point soon wore off and there was left a flat end which made a much thicker recording line after a certain amount of use than at the beginning; second, the stylus very frequently was bent to such degree as to render it inoperative; third, the stiff projecting stylus frequently cut into the record chart and tore and wrinkled the same so as to mar the record completely. These are among the many disadvantages which are connected with the use of the ordinary stylus heretofore employed, especially in connection with metallized paper.

It is one object of my invention to provide a metal stylus which will always make a record line of uniform thickness, which cannot possibly become bent in use, and which cannot catch in the paper to wrinkle, tear or otherwise obstruct the movement of the recording sheet.

Other objects and advantages of the invention will become apparent in the following detailed description thereof.

In the accompanying drawings,

Fig. 1 is a front elevation showing one application of my stylus to a record instrument.

Fig. 2 is a vertical section through one form of stylus embodying the principle of my invention, said stylus being shown in engagement with a record sheet.

Fig. 3 is a view similar to Fig. 2 showing the parts disassembled.

Fig. 4 is a vertical section through a second form of stylus embodying the principles of my invention.

Fig. 5 is a vertical section through still another form of stylus embodying the principles of my invention.

Fig. 6 is a plan view of the Fig. 5 form of the invention.

Fig. 7 is a vertical section showing an enlarged detail of the Figs. 5 and 6 form.

Referring to the drawings it will be observed that the form of stylus that I have here illustrated, while capable of general use is especially adapted for use in connection with a traveling record sheet 10, which in this case is designed to have recorded thereon the course of a vessel as determined by the course recorder 11, said chart traveling beneath one or more pens 12 adapted to mark a permanent record thereon. Preferably the record sheet is a metallized record sheet, that is, has a coating of some metal or metal-oxide and is adapted to be marked by a metal stylus.

In Figs. 2 and 3 I have shown in detail one form of stylus embodying the principles of my invention and said principles may be stated as follows:

First, instead of employing a free, unsupported metal marker I employ a marker 15 which is, however, completely surrounded, with the exception of a small projecting tip, by a holder 16. The marker 15 is, of course, of such material as will produce a mark on the metallized paper, this material being usually brass, while the support 16 is of non-marking material, such as iron or steel. I may provide the marker with the necessary resiliency in any suitable manner, as by making it of spring material with a bend, such as 17, therein. In either case the marker is of such length that when there is no tension thereon the point will project a short distance beyond the face 18 of the support 16 when not in engagement with the record sheet. When, however, the support 16 engages the record sheet, the pressure will be sufficient to cause the tip of marker 15 to lie substantially flush with the face 18. There is, therefore, no possibility of the marker becoming bent in service, nor can said marker engage in and catch any wrinkle in the surface of the paper to tear or otherwise obstruct the passage of the record sheet. I cause the face 18 to extend radially from the marker a distance at least three times the amount that said

marker projects beyond said face when not in engagement with the record sheet, so that if the support 16 is rolled out of the vertical position there will be no danger of bending the marker tip. If desired I may form the face 18 slightly convex to facilitate the movement of the marker over the record paper.

Referring to the details of Figs. 2 and 3 there is illustrated one method of assembling 10 a marker such as I have hereinbefore described. Where the marker is a single unit it may be a piece of spring wire as shown with one or more bends therein to permit compression of the spring wire when in engagement with the record sheet, said wire extending through a central opening 21 through the support to the face 18. The upper end of the marker may be held in a split cap 22 adapted to fit in a bore 23 in the upper end of the support 16. For locking the cap 22 within said bore the upper end of support 16 may be formed with a wedge-shaped top 24 upon which is adapted to fit a screw cap 25 having a cam-shaped inner bore 26 for receiving 15 said wedge portion 24. It will become at once apparent that upon screwing cap 25 downwardly the end 24 will be clamped more and more tightly against the split cap 22 to cause said cap to grip the end of the marker 20 firmly.

The principles of my invention may be embodied in a plurality of forms, several of which are disclosed in the remaining Figs. 4 to 7 of the drawings. Thus in Fig. 4 there is 25 a marker 15' of the same material as marker 15, within a support 16', said support carrying a projection 30 extending from one side thereof to provide the necessary initial bend in marker 15' to allow said marker to be compressed when in engagement with the record paper. The upper end of marker 15' in this instance may extend through the central aperture of a cap 25' and held in position by a thumb screw 32 extending through the 30 cap and into engagement with the spring marker 15'. A protecting member 33 may be inserted between the screw and the spring metal 15' to protect said metal against abrasion.

50 Figs. 5 and 6 disclose another modification somewhat similar to that of Fig. 4 except that the initial bend in marker 15' is produced by leading said marker through two openings 34-35 in one side wall of the casing 16''. In this case the upper end of marker 15' may be held in a block 40 in the same manner as said marker is held in cap 25' in Fig. 4 and the thumb screw 32 may extend through the wall of casing 16'' directly into 55 said block 40.

In accordance with the provisions of the patent statutes, I have herein described the principle and operation of my invention, together with the apparatus which I now consider to represent the best embodiment

thereof, but I desire to have it understood that the apparatus shown is only illustrative and that the invention can be carried out by other means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. A stylus for a recording chart of metalized paper and the like, comprising a holder of non-marking material having a face adapted to engage said chart, a resilient marker supported in said holder and normally projecting a predetermined distance beyond said face when out of contact with said chart, said marker having a bend therein to permit compression whereby it is substantially flush with said face when in contact with the chart.

2. A stylus for a recording chart of metalized paper and the like, comprising a holder of non-marking material, a thin wire metal marker supported in said holder and normally projecting beyond said holder, said marker being of uniform thickness throughout its length, means for anchoring said marker in said holder adjacent the inner end thereof, the bore of said holder being enlarged between the ends of the marker to permit flexure thereof.

3. A stylus for a recording chart of metalized paper and the like, comprising a holder of non-marking material, and a thin wire metal marker supported in said holder so that the end thereof projects beyond said holder, said marker being of uniform thickness throughout its length and having a bend therein to permit compression.

In testimony whereof I have affixed my signature.

LESLIE F. CARTER.
